UNITED STATES PATENT OFFICE.

LEANDER E. REYNOLDS, OF GRAND RAPIDS, MICHIGAN.

FILE-BOX.

SPECIFICATION forming part of Letters Patent No. 655,799, dated August 14, 1900.

Application filed December 16, 1899. Serial No. 740,609. (No model.)

To all whom it may concern:

Be it known that I, LEANDER E. REYNOLDS, a citizen of the United States, residing at Grand Rapids, in the county of Kent and 5 State of Michigan, have invented certain new and useful Improvements in File-Boxes; and I do hereby declare the following to be a full, clear, and exact description of the invention, such as will enable others skilled in the art to 10 which it appertains to make and use the same.

My invention relates to improvements in file-boxes, and more particularly to that class of file-boxes known as the "drop-front," in which the front of the box is hinged and 15 adapted to turn downward and expose the contents thereof; and its objects are to provide means for automatically moving the contents of the box forward and outward when the front is lowered, to provide a support for the 20 front when turned downward, to simplify the construction, and to provide the device with certain new and useful features hereinafter more fully described, and particularly pointed out in the claims.

25 My device consists, essentially, of a front attached to a hinged plate and a second plate 30 slidable longitudinally upon the hinged plate and having at the rear a vertical wall and rods connecting the front with the vertical 35 wall, whereby as the front is lowered the sliding plate and the rear wall are automatically moved forward, as hereinafter more fully described, and particularly pointed out in the 40 claims, reference being had to the accompanying drawings, in which—

Figure 1 is a perspective of a case containing four of my improved boxes with a portion of the case broken away to show the construction of the box and one of the said boxes 45 opened, as for inspection of the contents thereof. Fig. 2 is a longitudinal vertical section of the same through the middle of two of the boxes, and Fig. 3 an enlarged detail of one of the corner-braces.

50 Like letters refer to like parts in all of the figures.

A represents a suitable case to contain four of my improved boxes, which case may be for any convenient number of boxes and forms 55 no part of my invention.

B represents the front panels of the boxes, at-

tached to the front end of the plates C of substantially the same width as the front and having a hinge C' at a suitable distance from the front end thereof, whereby the forward portion of the hinged plate will turn downward at substantially right angles when the same is drawn out of the case a sufficient distance. D is a similar plate to support the contents of the box superposed upon the plate C and 60 slidable thereon and provided with a rear wall G at right angles thereto, and also provided with a longitudinal slot E, having an enlarged rear portion E' to permit the insertion and engagement of a flanged eyelet F, 65 rigidly secured in the bottom C, which eyelet serves to guide and hold the sliding plate D as it moves upon the plate C. In the respective angles between the front B and the hinged portion of the plate C are angle-braces 70 I, formed of suitable material, preferably of sheet metal, and provided with suitable flanges K for securing the same to the respective front B and plate C, and openings I' for pivotal engagement of the rods J, which rods 75 extend in parallel lines to the upper end of angle-braces H in the angle of the sliding plate D and the rear wall G, these braces being also provided with suitable flanges K for attachment to the plate D and rear wall 80 G. The upper portions of these angle-braces H are also provided with horizontal slots H', through which the rod J extends continuously and at right angles to its parallel sides, as at J', and in which slots it has sufficient movement to permit the front to move downward a sufficient distance to be out of the way of the contents of the box before the same begin to move outward. The rods J, it will be seen, 85 also serve as a support for the front by engagement with the case, as shown in Fig. 2. This rod consists of a wire pivotally secured at its respective ends to the upper part of the angle-plates I, and thence extending back and passing through the slots H' in the angle- 90 plates H and thence across the rear of the box.

The plates C and D and rear wall G can be made of any suitable material, preferably of thin millboard, and the flanges K of the angle-braces H and I are secured thereto by means of spurs L, struck up from the flanges, as

shown in Fig. 3, which spurs are inserted through the millboard and clenched down upon the same when the box is assembled.

The braces I may be secured to the front 5 B by suitable nails or screws passing through the flanges K instead of by spurs. It will be observed that when the box is drawn forward but a short distance the front thereof can be turned downward out of the way, and this 10 movement automatically brings the rear wall G and the sliding plate D forward, which plate supports the contents of the box, thus projecting the same outward in convenient position for inspection or removal. In like 15 manner when the box-front is closed the contents thereof are carried back and out of the way, also when the box is opened the front thereof is well supported by means of the rods J; also by this construction the angle-braces 20 form a strong and durable fastening to support the front B and the wall G at right angles to the plates C and D. The box having practically no obstruction at the sides will fully expose the contents for inspection and 25 access and take up less room than boxes having sides.

Having thus fully described my invention, what I claim, and desire to secure by Letters Patent, is—

30 1. The combination of a divided and hinged bottom plate, a front wall secured to the said plate, a plate slidable on the hinged bottom plate, a vertical rear wall attached to the sliding plate, and rods connecting the front 35 and the rear walls, substantially as described.

2. The combination of a divided and hinged bottom plate, a front attached thereto, a slid-

ing plate on the hinged bottom plate, a vertical rear wall on the sliding plate, slotted angle-braces connecting the rear wall and 40 sliding plate, and rods pivoted to the front and engaging the slots in said angle-braces, substantially as described.

3. The combination of a transversely-divided plate having a hinge, a sliding plate 45 resting thereon, a front wall attached to the front end of the divided plate, a rear wall attached to the rear end of the sliding plate, slotted braces connecting the sliding plate and the rear wall, angle-braces connecting 50 the front wall and the divided plate, and rods pivotally connected to the front angle-braces and engaging the slots in the rear angle-braces and movable therein, substantially as described.

4. The combination of a transversely-divided plate having a hinge, and a flanged eyelet therein, a front wall attached to the front end of the hinged plate, a sliding plate resting on the divided plate and having a slot 60 engaging the eyelet, a vertical wall attached to the rear end of the sliding plate, angle-braces connecting the sliding plate and the rear wall, and provided with slots, angle-braces connecting the front and the divided 65 plate and provided with openings, and rods pivotally engaging the openings and movably engaging the slots, substantially as described.

In testimony whereof I affix my signature in presence of two witnesses.

LEANDER E. REYNOLDS.
